UNITED STATES PATENT OFFICE.

WILLIAM H. JESSUP, OF MOUNT KISCO, NEW YORK.

TENSIONING MEANS FOR CLOTH-WINDING MACHINES.

Application filed April 12, 1921. Serial No. 460,705.

To all whom it may concern:

Be it known that I, WILLIAM H. JESSUP, a citizen of the United States, and resident of Mount Kisco, in the county of West-
5 chester and State of New York, have made a certain new and useful Invention in Tensioning Means for Cloth-Winding Machines; and I declare the following to be a full, clear, and exact description of the same, such 10 as will enable others skilled in the art to which it appertains to make and use the invention, reference being had to the accompanying drawings, and to letters or figures of reference marked thereon, which form a 15 part of this specification.

Figure 1 is a diagrammatic view showing the spindle, with the guide and tension devices, of a cloth-winding machine.

Figure 2 is a plan view of the preferred 20 form of tensioning bar.

Figure 3 is a detail fragmentary perspective view of the same.

The invention has relation to tensioning means for use with cloth-winding machines, 25 weaving machines, etc., being particularly adapted for use for winding cloth intended to be cut in the roll into narrow strips in the manufacture of tape or binding. The object of the invention is to provide im- 30 proved means to keep the cloth, warp or yarn at an even tension during the processes in question.

The invention consists in the novel construction and combinations of parts, as hereinafter set forth.

In the use of cloth-winding machines it has been found that the cloth will be tightly wound for six or seven inches at each end of the roll, while the middle portion will be 40 soft and spongy, this being due to the lateral stretching or flattening out incident to the usual tensioning of the material. That is to say, the material is able to flatten out properly at the free edges, but at the center 45 is unable to push the edges over sufficiently, and remains more or less bunched. A further consequence of this unequal winding is that the center threads will not feed straight, so that when the roll is cut considerable 50 ravelling will result. There is also much waste at the edges of the roll, due to uneven winding.

The present invention is designed to provide improved means to correct these defects 55 by applying a lateral tension to the goods being wound which will vary from the center

outward, to counteract the uneven lateral dis- placement above mentioned.

In the accompanying drawings, illustrating the preferred embodiment of the invention, the numeral 1 designates the spindle of a cloth-winding machine, 2, 2, the guide rollers and 3, 3, the usual tension rolls of such machine.

Between the guide rollers and the spindle 65 is secured the improved tensioning device, consisting of a rigidly mounted bar 4, over which the cloth passes. The bar 4 is so positioned as to deflect the cloth in its passage from the guide rollers to the spindle, caus- 70 ing it to have substantial frictional contact with a face 5 of said bar. Diagonal grooves 6 are formed in the face 5, the grooves upon each side of the center extending toward their respective edges, with relation to the 75 direction of movement of the cloth. The projections 7 left between these grooves will thus have diagonal marginal edges along the diagonal groove walls 8 which, in the frictional contact of the cloth moving over 80 the face 5, will deflect the portions contacting therewith and cause said cloth to be stretched from the center outwardly toward the edges.

An equal degree of deflecting resistance, 85 from the center to the edge, added to the normal lateral pushing tendency, which is most effective at the edges, would result in a roll wound more tightly at the edges than in the center. Therefore the grooves 6 are 90 spaced with decreasing intervals therebetween from the edges to the center, whereby the number of diagonal deflecting walls 8 acting upon a given width of cloth will be greatest at the center, and the action upon 95 this portion of the goods will be increased correspondingly.

Lateral faces 5', 5'', of the bar 4 intersect the contact face 5, the grooves 6 of the latter appearing upon these faces as notches 100 6'. The bar 4 is so positioned that the course of the cloth will be deflected at the edges formed by the intersection of face 5 with faces 5' and 5''. Thus the cloth in approaching the face 5 will have portions 105 thereof pulled into the notches 6' of face 5', while in leaving the face 5 portions will be pulled into the notches 6' of face 5'', whereby the entry of the cloth into the grooves 6 and the grip thereon of the walls 8 will be greatly 110 assisted.

By the use of this device cloth may be

rolled and cut into widths or tape rolls of even firmness; ravelling is practically eliminated, and a minimum wastage occurs in trimming the ends of the original roll; the saving in labor and material being very considerable and the product more satisfactory.

I claim:

1. In combination with a cloth-winding machine having a guide roller and a spindle, a tensioning device comprising a bar provided with a diagonally grooved contact face adapted to tension the cloth laterally and to impart a decreasing tension from the center to the edges thereof, and a lateral face intersecting said contact face and notched by the grooves thereof, said bar being rigidly mounted with the edges formed by the intersection of said faces in position to deflect the cloth in its passage from said guide roller to said contact face and from said contact face to said spindle.
2. In combination with a cloth-winding machine having a guide roller and a spindle, a tensioning device comprising a bar provided with a diagonally grooved contact face adapted to tension the cloth laterally and to impart a decreasing tension from the center to the edges thereof, and lateral faces intersecting said contact face and notched by the grooves thereof, said bar being rigidly mounted with the edges formed by the intersection of said faces in position to deflect the cloth in its passage from said guide roller to said contact face and from said contact face to said spindle.

In testimony whereof I affix my signature 35 in presence of two witnesses.

WM. H. JESSUP.
